UNITED STATES PATENT OFFICE

IRVING H. DUNN, OF FAIRFIELD, IOWA, ASSIGNOR TO THE DEXTER COMPANY, OF FAIRFIELD, IOWA, A CORPORATION OF IOWA

OPERATING GEARING FOR WASHING MACHINES AND THE LIKE

Application filed June 18, 1928. Serial No. 286,273.

This invention relates to operating gearing for machines and the like, and consists of the matters hereinafter described and more particularly set out in the appended claims.

5 The object of the invention is to provide a novel and improved gearing of simple and economical construction and capable of ready and easy assembly, designed primarily for the operation of the agitator of a washing machine wherein the agitator is of the inverted dolly type and operates in close relation to the tub bottom through which extends the operating shaft.

10 In such a washing machine the agitator is driven from a point located considerably above the tub bottom and above the normal water level therein, where it is connected to the operating shaft, which is actuated and given an alternating rotary movement by 15 gearing located below the tub and there connected to a drive shaft.

The several objects and advantages of the invention will appear more fully as I proceed with my specification.

25 In the drawings:—

Figure 1 is a view representing a vertical central section through a washing machine of the kind described and provided with my improved gearing.

30 Figure 2 is a view on a somewhat enlarged scale showing a horizontal section through the gearing in a plane indicated by the line 2—2 of Figure 1.

Figure 3 is a view representing a partial section in a plane indicated by the line 3—3 of Figure 1, illustrating the parts of the gearing in a different position from that shown in Figure 2.

35 Referring now to that embodiment of the invention illustrated in the drawings:—10 indicates the receptacle or tub of a washing machine. The tub as illustrated and preferred, is made of copper with a bottom wall 12 and a cylindrical vertical side wall 13. 14 indicates a vertical operating shaft which extends upwardly through an aperture 12^a in the tub bottom. 15 indicates the agitator with its tubular baffle member 15^a extending upwardly to the top end of the shaft 14. 16 40 is a tubular stem surrounding the shaft 14 and rising from the tub bottom (being supported in a manner presently to be described) and providing at its upper end bearing for the upper end of the shaft 14. A polygonal head 17 fixed to the top end of the shaft 14 and bearing against the top end of the tubular stem 16 provides for removable attachment of the top end of the tubular baffle member 15^a of the agitator. A knurled cap 18 engaged on a screw projecting upwardly 45 through the top of the head 17 retains the agitator in operative engagement with the head 17.

Below the tub bottom and extending diametrically thereof, is a gear casing comprising a top shell 19 and a bottom shell 20. The top shell 19 has an integral tubular bearing 21 located at the center of the tub bottom with a threaded part 21^a which extends upwardly 50 through the aperture 12^a in the tub bottom and upon which is screwed the bottom end of the tubular stem 16. Said stem has a bottom radial flange 16^b, which, with an annular boss 19^a on the shell 19 formed about the bearing 21, engages between them the tub bottom wall 55 12, thus providing a rigid support for the tubular stem 16 and a watertight seal between the bottom end of said stem and the bottom wall of the tub.

The bottom end of the shaft 14 is mounted 60 in the bearing 21 and has thrust bearing at 14^a in a boss formed in the bottom shell 20 of the casing. A pinion 22 is fixed to the shaft 14 at its lower end in the neighborhood of the bottom of the shell 20.

65 23 indicates an auxiliary gear casing attached to the bottom member 20 of the main gear casing at the periphery of the tub. 24 is a short vertical drive shaft extending from the auxiliary gear case up into the main gear case and provided with suitable bearings in both. Said auxiliary gear case contains a worm 25 which drives a worm gear 26 fixed on the shaft 24.

A crank arm 27, fixed to the shaft 24 in the 70 main gear casing, has fixed to it one end of a stud 28, which in turn has attached to its opposite end a crank arm 29 extending parallel to the first crank arm 27 and with the same axis of rotation. 30 indicates a shaft extend- 75

ing vertically alongside the tub through a tube 31 for operating the usual wringer mechanism. Said shaft has its axis of rotation in vertical alignment with that of the shaft 24 and has the crank arm 29 fixed to its bottom end.

- 10 The stud 28 provides a crank pin on which is pivotally mounted a coupling 32 located between the two crank arms 27 and 29. A horizontal rod 33 connects the coupling 32 to a coupling 34 located near the pinion 22. 35 indicates a short rack bar (see Figures 2 and 3) located below the plane of the rod 33 and adapted for engagement with the pinion 22. 15 The coupling 34 is pivoted on a stud 36 rising from the rack bar 35, which is thus operatively connected through the rod 33 and the two couplings 32 and 34, constituting a pitman rod, to the crank pin or stud 28. 20 Located in the plane of the rack bar 35 and adjacent the bottom wall of the shell 20 is a rod 37 extending in general parallel relation to the pitman rod 33. Said rod 37 has fixed to one end a coupling 38 by means 25 of which it is pivotally connected to a vertical stud 39 rising from and attached to the bottom wall of the shell 20. The rack bar 35 has laterally disposed, spaced, apertured ears 40, 40 which have sliding bearing on the 30 rod 37.

35 The casing comprising the two shells 19 and 20 terminates just beyond the pinion 22 and there the top shell 19 has a lower horizontal part 41 with an aperture to receive a bearing plug 42 which snugly fits the aperture but is capable of a rotative movement for purposes of adjustment. To this end the plug, as shown, has a polygonal head to be engaged by a wrench. Eccentrically mounted 40 in said bearing plug is a short vertical rock shaft 43 having an arm 44 rigid therewith located below the bearing plug within the gear casing and carrying a depending pin 45. A crank arm 46 is fixed to the rock shaft 43 above the part 41 of the shell 19. The depending pin 45 engages in a slot 43^a presented as shown by a forked member 47 fixed to the proximate end of the rod 37. From an examination of Figures 2 and 3, it will 50 be obvious that by rocking the shaft 43, the depending pin 45, by its engagement in the slot 43^a, may be made to swing the rod 37 upon its pivotal connection with the stud 39, thereby moving the rack bar 35 into or out 55 of engagement with the pinion 22. It will also be apparent that by rotating the bearing plug 42, the horizontal location of the rock shaft 43 (eccentrically mounted therein) with reference to the pitch line of the pinion 22, may be varied. Thus when assembling the gearing the operative position of the rack bar 35 may be accurately adjusted for proper engagement of the rack 60 bar with the pinion 22; and later, after the

gearing has had long continuous use, it may be adjusted to compensate for wear.

A vertical rock shaft 48 located at the side of the tub 10 and mounted in suitable bearings 49, 58 at the bottom and top of the tub, 70 presents through an arm 51, at the top of the tub, means for operating the rock shaft 43. A rock arm 52 fixed to the bottom of said shaft 48 is operatively connected by a rod 53 and couplings 54, 55 to the said rock shaft 43 so that the rock shaft 43 may be manipulated by the arm 51 at the top of the tub to move the rack bar 35 into engagement with the pinion 22, to impart an alternating, rotary movement to the operating shaft 14 by the rotary movement of the main shaft 24; or by a reverse movement, to withdraw said rack bar from engagement with the pinion 22, thus disconnecting the operating shaft 14 from the main drive shaft 24. 80

The main gear casing comprised of the top and bottom shells 19, 20 and the auxiliary gear casing 23 carried by the bottom shell 20, all of which may be made oil tight, entirely enclose the main shaft 24, the worm and gear for driving it, and all the gearing and connections between said main drive shaft, the wringer mechanism shaft 30, and the operating shaft 14 and including the operating mechanism for connecting and disconnecting the operating shaft 14 with respect to the drive shaft 24. A smooth, easy and noiseless operating gearing, as well as an easily operated disengaging mechanism for the operating shaft, is thus provided. 90

I claim as my invention:

1. In a gearing for washing machines and the like, a drive shaft, an operating shaft, a pinion fixed to said operating shaft, a rack bar for engagement therewith, a pivoted rod on which said rack bar is slidably mounted, means connecting said rack bar and drive shaft for reciprocating said rack bar on said rod, a rock shaft at the free end of said rod, an arm on said rock shaft operatively engaged with said rod, and a plug capable of rotative movement in which said rock shaft has eccentric bearing. 105

2. In a gearing for washing machines and the like, a gear casing, a drive shaft, an operating shaft, both shafts having bearings within said casing, a pinion fixed to said operating shaft within the casing, a rack bar for engagement with said pinion, a pivoted rod on which said rack bar is slidably mounted, means connecting said rack bar and drive shaft for reciprocating said rack bar on said rod, a rock shaft adjacent the free end of said rod, means within the casing operatively connecting said rock shaft with said rod, a plug in which said rock shaft is eccentrically mounted, said plug being capable of rotative movement and being provided with a head without the casing presenting means to bring about said movement, 120 125 130

and means without the casing operatively connected to said rock shaft for rocking the same.

5 In testimony that I claim the foregoing as my invention, I affix my signature this 12th day of June, A. D. 1928.

IRVING H. DUNN.
